UNITED STATES PATENT OFFICE.

RUSSELL P. AMBLER, OF DE FUNIAK SPRINGS, FLORIDA.

BICYCLE.

SPECIFICATION forming part of Letters Patent No. 634,789, dated October 10, 1899.

Application filed December 12, 1898. Serial No. 699,033. (No model.)

To all whom it may concern:

Be it known that I, RUSSELL P. AMBLER, a citizen of the United States, and a resident of De Funiak Springs, in the county of Walton 5 and State of Florida, have invented certain new and useful Improvements in Bicycle Driving-Gear; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a side elevation of a portion of a bicycle having my invention applied thereto. Figs. 2, 3, 4, 5, and 6 are detail views showing portions of the parts of my device at different points in the stroke.

20 This invention has relation to certain new and useful improvements in bicycle driving mechanism, and is more particularly designed as an improvement upon the driving mechanism described and claimed in my Patent 25 No. 609,722, issued August 23, 1898.

The particular objects of the present invention are, first, to provide for a more effective leverage to carry the cranks past the vertical centers, and, second, to so arrange the supplemental foot-levers that their relation to the pedal-levers remains unchanged during the entire stroke.

With these objects in view the invention consists in the novel construction and combination of parts, all as hereinafter described, and pointed out in the appended claims.

Referring to the accompanying drawings, the letter A designates the crank-shaft hub or hanger of a bicycle.

40 B designates the crank-shaft; C, the cranks at the ends of said shaft; D, the pedal-levers connected to said cranks; E, the supplemental foot levers or arms which form branches of the pedal-levers, and F the fulcrum-arms 45 for the levers D, said arms having at their lower portions oblong slots f, which are inclined upwardly and rearwardly and which loosely engage stationary pins or studs g, which are carried by rigid arms G, which de-

pend from the hub or hanger A in a perpendicular line. The said pins or studs are pref-

erably about six inches below the crank-shaft center; but this distance may be varied.

The supplemental levers E are rigidly secured to the pedal-levers D and have downwardly-extending end portions E', which project below the pedal-levers and are designed in certain positions to take a bearing against the fulcrum-arms F below the points of pivotal connection of the latter with the pedal-levers, as shown in Figs. 2 and 3. The fulcrum-arms F are provided with extensions F' above the pedal-levers, and these extensions in certain positions of the levers are arranged to be impinged upon by the rear portions of 65 the supplemental levers E, as shown in Fig. 5. The cranks C, pedal-levers D, supplemental levers E, and fulcrum-arms F exist in duplicate upon the two sides of the machine, the two cranks C being one hundred and eighty 70 degrees from each other. The free end portions of the levers E terminate over the pedals and are provided with suitable pads for the foot, as in my said patent.

P designates the sprocket chain and gear, 75 which connects the pedal-shaft with the hub of the rear driving-wheel R. Any suitable gear connection may, however, be employed.

The operation is as follows: Fig. 2 shows the pedal-lever on the downstroke, with the 80 crank C at a position of about three hundred and forty degrees, the fulcrum-arm F being substantially perpendicular with the pin or stud g at the higher end of the slot f. In this position the pedal-lever is nearly 85 at the limit of its effective stroke, while the crank has yet to pass the top center before the pedal-lever begins its up movement. At this time the end portion E' of the lever E takes a bearing against the fulcrum-arm F 90 below the point X of pivotal connection of said arm with the lever E, and thereby pushes the lower arm of said lever rearwardly, the slot f riding on the pin or stud g until the lower end of the slot strikes said pin or stud. 95 During this movement (the pressure on the pedal being continued) the crank is carried past the center and the fulcrum-point X is moved upward and forward to an extent equal to the upward and forward movement of the 100 end of the crank in passing center, (the inclination of the slot f being sufficient to give

this amount of vertical movement,) the effect of the movement of said fulcrum-arm being to provide a new and changing fulcrum for the lever D during this part of its downstroke.

5 The upstroke now commences, the rider pulling upward with his foot on the lever E, and the crank moves forward and downward. Fig. 3 shows the position of the parts at this time. During this stroke the fulcrum-arm 10 F and fulcrum-point X assume successively the positions shown in Figs. 4 and 5. When the parts are in the position shown in Fig. 5, the pedal-lever D has nearly reached the 15 limit of its upstroke and the crank is approaching the lower center. At this time the rear portion of the lever E comes in contact with the extension F' of the fulcrum-arm F above the fulcrum-point X, and thereby forces the lower portion of said lever forwardly, carrying the fulcrum-point X downwardly and rearwardly and the crank past the center. The position of the parts at this time is as shown in Fig. 6.

Having thus described my invention, what 25 I claim as new, and desire to secure by Letters Patent, is—

1. In a bicycle driving mechanism, the combination of a shaft having cranks, pedal-levers connected to said cranks, fulcrum-arms to 30 which said pedal-levers are intermediately fulcrumed, and which at their lower portions have a shiftable pivotal connection with the frame, the supplemental levers or arms connected to the pedal-levers and terminating at 35 their free portions adjacent to and above the pedals thereof, and means whereby said ful-

crum-arms are shifted at certain times, substantially as specified.

2. In a bicycle driving mechanism, the combination with a shaft having a crank, of a 40 pedal-lever connected at one end to said crank, a supplemental lever or arm connected to said pedal-lever and having its free end portion terminating above and adjacent to the pedal thereof, and its opposite end extended below the pedal-lever, and the fulcrum-arm shiftably connected to the frame at its lower portion and to the upper portion of which the pedal-lever is fulcrumed, said fulcrum-arm and supplemental arm or lever 45 being relatively arranged whereby their end portions will impinge upon each other in two different positions to thereby shift said fulcrum-arm, substantially as specified.

3. In a bicycle driving mechanism, a 50 cranked shaft, a branched pedal-lever, one branch of which is arranged to receive downward pressure of the foot and the other branch upward pressure of the foot, and an arm 55 shiftably and pivotally connected to the frame at its lower portion and to the upper portion of which the pedal-lever is fulcrumed, one branch of said pedal-lever being arranged to impinge upon said arm and shift the same at 60 certain points in the movement of said lever, substantially as specified.

In testimony whereof I affix my signature in presence of two witnesses.

RUSSELL P. AMBLER.
